DESIGN FOR A FINGER RING OR THE LIKE

Nathan Hershau, New York, N. Y.

Application March 2, 1935, Serial No. 55,695

Term of patent 3½ years

To all whom it may concern:

Be it known that I, Nathan Hershau, a citizen of the United States of America, residing at New York city, county and State of New York, have invented a new, original, and ornamental Design for a Finger Ring or the like, of which the following is a specification, reference being had to the accompanying drawing, forming a part hereof, wherein the figure is a perspective view of a finger ring showing my new design.

I claim:

The ornamental design for a finger ring or the like substantially as shown.

In witness whereof, I have signed this application.

NATHAN HERSHAU.
